UNITED STATES PATENT OFFICE

112,110

DESIGN FOR A TEXTILE FABRIC

Curt E. Forstmann, Montclair, N. J.

Application February 16, 1938, Serial No. 75,192

Term of patent 14 years

To all whom it may concern:

Be it known that I, Curt E. Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design comprises warpwise stripes having a sinuous pattern, adjacent stripes co-operating and forming diamonds and groups of two prominent stitches at the corners of the diamonds, as shown.

I claim:

The ornamental design for a textile fabric, as shown and described.

CURT E. FORSTMANN.
